BEAM INTERACTION DEVICES

Robert Adler, Northfield, Ill., assignor to Zenith Radio Corporation, a corporation of Delaware

Application April 1, 1954, Serial No. 420,430

17 Claims. (Cl. 313—70)

This invention is directed to a new and improved electron-discharge device and more particularly to a beam-interaction device in which the intensity of one beam of electrons is controlled in accordance with variations in the intensity of a second electron beam.

The figure of merit of an electron-discharge device employed as an amplifier, modulator, etc., is directly proportional to the transconductance g_m and inversely proportional to the grid-cathode and plate-cathode capacities of the device, and its useful frequency range is directly related to the figure of merit. Consequently, it may be stated that a tube to be employed as a broadband amplifier should have a high transconductance and a minimum of interelectrode capacity. The latter requirement is inconsistent with the use of large-area anodes and/or control electrodes, inasmuch as the anode and control electrode capacities are directly related to the areas of these elements.

One suggested form of electron-discharge device employs two separate beams projected through an interaction region at right angles with respect to each other. One of these beams, which carries substantially less current than the other of the beams, is intensity-modulated by means of a control grid. The changes in intensity of the first beam result in corresponding variations in space charge density in the common space traversed by the two beams so that the second or high-current beam is to a certain extent velocity-modulated in accordance with the intensity-modulation of the low-current beam. Another somewhat similar proposal employs two electron beams projected in opposite directions along parallel paths closely adjacent to each other. In this device, deflection-modulation of one beam produces space charge variations in the region between the two beams so that the second beam is similarly deflection-modulated. Each of the described prior-art devices represents an attempt to modulate an electron stream without the use of conventional deflection plates or a conventional intensity-control grid. However, devices of this type have not been markedly successful and have not been adopted commercially because the useful gain available from modulation of one beam in accordance with variations in a second beam is small as compared to the amplification which may be achieved by more conventional tubes.

It is an object of this invention, therefore, to provide a new and improved electron-discharge device having a relatively high figure of merit and suitable for use as a broad-band amplifier.

It is a further object of the invention to provide a new and improved beam-interaction electron-discharge device which provides relatively high amplification.

It is an additional object of the invention to provide a new and improved electron-discharge device which provides high gain with a minimum of external circuits and connections.

It is another object of the invention to provide a new and improved beam-interaction device which is simple

and expedient to construct and economical to manufacture.

An electron-discharge device constructed in accordance with one aspect of the invention comprises means including a first electron gun for projecting a first sheet-like beam of electrons along a first reference path and means including a second electron gun for projecting a second sheet-like beam of electrons along a second reference path, a part of the second path being coincident with a part of the first reference path. The device further includes an additional electrode system, encompassing at least a part of the coincident parts of the reference paths; this additional electrode system comprises a retarding electrode which is associated with and co-operates with the second electron gun to establish a virtual cathode region in which the intensity of the second electron beam is determined by the intensity of the first electron beam. Control means are coupled to at least a portion of the first beam and are responsive to an applied signal to control the intensity of that portion of the first beam. In addition, the device includes output means coupled to at least a portion of one of the electron beams to derive an output signal therefrom.

An electron-discharge device constructed in accordance with another aspect of the invention comprises means including a first electron gun for projecting a first sheet-like beam of electrons along a first reference path and means including a second electron gun for projecting a second sheet-like beam of electrons along a second reference path with increments of each of the two electron beams intercepting more than one similar increment of the other beam. Two additional electrode systems are included in the device; these additional electrode systems are associated with and co-operate with the electron guns to establish two spaced electron-interaction regions in each of which one of the electron beams is controlled by the other of the beams. Control means are coupled to at least a portion of the first electron beam and are responsive to an applied signal to modulate that portion of the first beam. In addition, the device includes output means coupled to at least a portion of one of the electron beams to derive an output signal therefrom.

The features of the invention which are believed to be novel are set forth with particularity in the appended claims. The organization and manner of operation of the invention, together with further objects and advantages thereof, may best be understood by reference to the following description taken in conjunction with the accompanying drawings, in which like reference numerals indicate like elements in all figures, and in which:

50 Figure 1 is a cross-sectional view of an electron-discharge device constructed in accordance with the invention and includes a schematic representation of an amplifier circuit for the device;

55 Figure 2 is a view of the electrode systems of the tube shown in Figure 1, taken along line 2—2 therein;

Figure 3 is a schematic representation of an electron-discharge device comprising another embodiment of the invention;

60 Figures 4A, 4B and 4C are explanatory diagrams illustrating certain electrical characteristics of the electron tube of Figure 3;

Figure 5 is a schematic representation of another embodiment of the invention; and

65 Figure 6 is an explanatory diagram employed to describe the operation of a portion of the device of Figure 5.

The embodiment of the invention illustrated in Figure 1 comprises an electron-discharge device 10 including a first electron gun 11 and a second electron gun 12 both mounted within a single evacuated envelope 13. Electron gun 11 comprises a cathode 14, a first focusing electrode 15, and an accelerating electrode 16. An additional

electrode system 21 is associated with gun 11 and comprises a pair of focusing electrodes 17, a retarding electrode or grid 18 and an anode 23; the electrodes of gun 11 and system 21 are disposed in the order named along a reference plane A. Focusing electrode 15 may comprise a sheet of conductive material including an aperture 19 which is symmetrical with respect to reference plane A, and accelerator 16 may be of similar construction and may include an aperture 20 aligned with reference plane A. Focusing electrodes 17 may be constructed from conductive rods or similar suitable elements, and grid 18 may comprise a plurality of conductive wires mounted on a pair of support elements 22 and spaced from each other in a direction perpendicular to the plane of the drawing. Electron gun 12, which is preferably disposed symmetrically with respect to reference plane A opposite gun 11, includes a cathode 24, a focusing electrode 25 having an aperture 26 encompassing plane A, and an accelerating electrode 27 including a slot 28 which is aligned with the reference plane. A second electrode system 36 is associated with gun 12 and includes a pair of focusing electrodes 29, a retarding electrode in the form of a grid 30, and an anode 31 which may be electrically connected to or formed integrally with anode 23 of system 21. Anodes 23 and 31 include individual apertures 34 and 35 respectively, the two apertures encompassing reference plane A.

As thus far described, the individual electrodes of guns 11 and 12 and electrode systems 21 and 36 may be constructed to be essentially similar to each other; in other words, the physical and electrical characteristics of cathodes 14 and 24 may be made as nearly identical as possible, focus electrodes 15 and 25 may have substantially similar configurations and may be made from the same conductive material, and the various other electrodes in each system may similarly be identical in construction to the corresponding electrodes of the other system.

As indicated in Figure 2, which shows the electrode systems of device 10 from a different aspect, it is preferred that the electrodes of the tube be substantially greater in height than the width of the apertures formed in the electrodes. Furthermore, in this embodiment of the invention, the two electrode systems are displaced with respect to each other by an acute angle designated θ . This view also shows more clearly the relative size and position of a control electrode or grid 32 included in electrode system 21 and positioned to be substantially co-planar with the grid elements of retarding electrode 18. An anode or collector electrode 33 is positioned intermediate anode 31 and retarding electrode 30 and extends transversely of reference plane A, as indicated in Figure 1; anode 33 is mounted above apertures 34 and 35 so that it intercepts only the electron stream developed by gun 12 and translated through system 36.

Figure 1 also shows a simplified schematic circuit for tube 10. Cathode 14 is connected to focus electrodes 15 and 17 and is also connected to a source of reference potential, here indicated as ground. Similarly, cathode 24 and focus electrodes 25 and 29 are all interconnected and are connected to ground. Accelerating electrodes 16 and 27 are each connected to a source of positive unidirectional operating potential B_1+ , whereas anodes 23 and 31 are conductively coupled to a second source of positive operating potential B_2+ . Collector electrode 33 is connected through a load resistor 86 to another source of positive unidirectional potential B_3+ . Retarding electrodes 18 and 30 are individually coupled to a variable bias potential source 37, and control electrode 32 is coupled to a single source 38.

The operation of electron-discharge device 10 may perhaps best be understood by first considering the somewhat simpler embodiment of the invention illustrated in Figure 3. In this embodiment, a discharge device 39

comprises a first electron gun 40 and a second electron gun 41. Electron gun 40 includes a cathode 42, a control electrode 43, a focusing electrode 44, and an accelerating electrode 45. The electrodes of system 40 are arranged symmetrically with respect to a reference path indicated by short dash line C; electrodes 44 and 45 are provided with suitable apertures centered about the reference path. Electron gun 41 comprises a cathode 46, a focusing electrode 47, and an accelerator 48. An additional electrode system 49 is associated with and cooperates with electron gun 41; system 49 includes a focusing electrode 50, a retarding grid 51, and an accelerating electrode 52. The electrodes of gun 41 and system 49 may be essentially identical in construction with the corresponding elements of electron gun 12 and electrode system 36 of Figure 1; the individual electrodes are preferably symmetrically arranged about a reference path indicated by dash line E.

As indicated in the drawing, electron guns 40 and 41 are preferably angularly displaced with respect to each other so that beam reference paths C and E would normally intersect. However, as will be explained more completely hereinafter, the two reference paths do not cross but are made to coincide in part with each other. A solenoid 53 is mounted within tube 39 in the general region in which the two reference paths would normally cross; the axis of the solenoid extends perpendicularly to the plane of the drawing. Coil 53 is preferably wound from extremely fine wire so that it intercepts only a very small portion of the two electron beams generated by guns 40 and 41; the coil may be mounted on a pair of insulating support members 54 formed from ceramic material, mica, or any other suitable insulator. A collector electrode 55 is disposed transversely of reference path E on the side of solenoid 53 opposite electrode system 49.

It will be recognized by those skilled in the art that electron gun 41 and electrode system 49 together comprise a simplified version of a gated-beam tube. In order to understand the operation of tube 39, operation of this section of the tube will first be considered independently of the operation of electron gun 40. For this purpose, cathode 46, focusing electrodes 47 and 50 and retarding electrode 51 may all be connected to a source of reference potential, here taken as ground. Accelerating electrodes 48 and 52, on the other hand, are connected to suitable sources of unidirectional positive operating potential generally indicated as B_+ . Coil 53 is connected through accelerator 52 to positive D.C. source B_+ . The coil is also connected to a source of operating potential shown as a battery 88, a suitable variable resistor 56 being included in the coil circuit. Collector electrode 55 is also connected through a load resistor 87 to positive operating potential source B_+ ; it will be understood that the actual operating potentials applied to anodes 48, 52 and 55 need not necessarily be the same.

When the apparatus of Figure 3 is placed in operation, a stream of electrons emitted from cathode 46 is focused and accelerated as it passes through the apertures of electrodes 47 and 48 to form a sheet-like beam of electrons centered about reference path E. The term "sheet-like beam," as used throughout this specification and in the appended claims, refers to any electron stream having one characteristic cross-sectional dimension which is very much smaller than the other. Preferably, the sheet-like beam may be of elongated rectangular configuration, in accordance with the indicated configuration of accelerator slot 20 (Figure 1).

As the beam emerges from the slot in accelerator 48, it is again focused as it passes through the aperture in electrode 50. Subsequently, the beam passes through retarding grid 51 and continues along path E, entering the magnetic field within solenoid 53. The magnetic field of the coil deflects the electron beam so that it impinges upon collector anode 55, which may be made relatively

large in size to insure interception of the entire beam over a reasonable range of magnetic field intensities. If the beam is sharply focused, a major portion of the electrons passes through the aperture in anode 52 to impinge ultimately upon anode 55.

The region intermediate accelerator 48 and retarding grid 51 is characterized by a high space-charge density, providing the proper electrode spacings and voltages are maintained, as exemplified by gated-beam tubes such as the commercial type 6BN6. This high space-charge density region constitutes a virtual cathode, provided the operating potential on retarding grid 51 is low enough so that a portion of the electron beam is reflected back toward accelerator 48. For any given operating condition, there exists a plane of minimum potential indicated by dash line 57 within this virtual cathode region. If electrons from an external source are introduced into the virtual cathode region, the plane of minimum potential tends to move toward cathode 46, as indicated by dash line 58, and the number of electrons passing through retarding electrode 51 to reach the slot in accelerator 52 may be sharply reduced.

If electron gun 40 is biased beyond cut off and a variable voltage is applied to grid 51, the operating characteristic of the apparatus of Figure 3 corresponds generally to that shown in Figure 4A, in which i_{55} represents the plate current drawn by anode 55 and is plotted against e_{g51} , the voltage applied to the retarding grid 51. This operating characteristic is a familiar step-function typical of devices of the gated-beam type.

In order to determine the operating characteristics of electron gun 40, cathode 42 and focus electrode 44 may be connected to ground potential and accelerator 45 may be connected to a suitable source of positive operating potential B+. At the same time, all of the electrodes of gun 41 and system 49 may be interconnected to each other and to positive operating potential source B+. A variable voltage may then be applied to control electrode 43, as from a signal source 59. Electron gun 40 then generates a stream of electrons which pass through control electrode 43, and are focused and accelerated into a sheet-like beam as they traverse the apertures in electrodes 44 and 45. The electron beam from gun 40 follows path C and enters the magnetic field of solenoid 53; the magnetic field deflects the electron beam so that path C extends in substantial coincidence with path E and passes through the aperture in accelerator 52 to impinge upon the various electrodes of gun 41 and system 49. By varying the potential of control electrode 43, the grid voltage-plate current characteristic illustrated in Figure 4B is obtained. In Figure 4B, a symbol i_{40} refers to the total current collected by the electrodes of gun 41 and system 49 and e_{g43} represents the potential applied to control electrode 43.

For operation in accordance with the invention, electron gun 41 and electrode system 49 are reconnected as illustrated and placed in operation with retarding electrode 51 biased to develop a preselected plate current I_0 (Figure 4A). In the illustrated embodiment, I_0 is taken as the current intercepted by anode 55 with retarding electrode 51 grounded. Moreover, the strength of the magnetic field developed by solenoid coil 53 is adjusted so that a substantial portion of the electron stream from gun 40 passes through the aperture in accelerator 52 and is projected into the virtual cathode region between electrodes 50 and 51; control of the magnetic field strength may be achieved by adjusting variable resistor 56 to vary the current through coil 53.

With both electron guns in operation, and with a substantial portion of the beam from gun 40 projected into the virtual cathode region established by electrode system 49, the current drawn by anode 55 varies in accordance with curve i_{55} (Figure 4C) as the voltage e_{g43} on control grid 43 is varied. For convenience, the beam current i_{40} of electron gun 40 is similarly plotted to the same scale in Figure 4C. For any grid voltage at which the nega-

tive slope of curve i_{55} is greater in absolute value than the positive slope of curve i_{40} , the rate of decrease of the current at plate 55 exceeds the rate of increase of the beam current of gun 40. It has been found that the interaction factor for the electron beam developed by gun 41 and translated through system 49, which factor may be defined as the ratio of the negative slope of curve i_{55} to the positive slope of curve i_{40} at the operating point, may be greater than unity and that gain may be achieved from the tube.

A signal applied to control grid 43 may be utilized to control the intensity of the electron beam from gun 40 and the intensity of the electron beam from gun 41 is controlled, in the virtual cathode region established by retarding electrode 51 and focus electrode 50, in accordance with the intensity of the beam from gun 40. Accordingly, the signal applied to grid 43 appears in amplified inverted form at collector electrode 55. The two electron beams are effectively segregated from each other by the magnetic field of coil 53 according to the direction from which the electrons enters the magnetic field.

Tube 39 may be constructed to provide a substantial amount of gain, but may not achieve as much amplifications as may be realized in a two-stage amplifier constructed with conventional grid-control tubes. In the embodiment of the invention illustrated in Figures 1 and 2, the gain is effectively cascaded to provide even greater amplification so that several tubes may be replaced by a single device without sacrificing gain. When tube 10 is placed in operation, a stream of electrons emitted from cathode 14 is focused and accelerated as it passes through apertures 19 and 20 of electrodes 15 and 16 to form a sheet-like beam of electrons which enter the interaction region or virtual cathode established by focusing electrodes 17 and retarding grid 18.

Similarly, a second stream of electrons is developed at cathode 24 and is focused and accelerated as it passes through electrodes 25, 27 and 29. Each of the electron beams continues through anode slots 34 and 35 and extends into the interaction region of the other beam, so that a change in intensity of one beam results in an amplified change of opposite sense in the other beam. Stated differently, an increase in the intensity of electron beam generated by gun 11 and translated through system 21 causes an even greater decrease in the intensity of the electron beam developed in electron gun 12 and translated through system 36, which, in turn, results in an even further and greater increase in the intensity of the beam from gun 11.

If the two beams were aligned directly opposite to each other, the device would be unstable or would tend to produce oscillation, since any change in intensity of either beam would continue to build up until the two beams reached their respective maximum and minimum intensities. This instability is avoided, in this embodiment, by angularly displacing the electrodes of the two systems while maintaining their substantial symmetry about a common center plane as illustrated in Figure 2 so that their respective reference paths intersect within plane A at an acute angle θ . Moreover, the means employed for modulating the intensity of one of the beams, control grid 32, is so located that it intercepts only a fractional portion of the beam. Consequently, with both sections of the tube in operation, a signal to be amplified may be applied from source 38 to control grid 32. If the applied signal instantaneously increases the potential of electrode 32, the fractional portion of the first electron beam, developed in system 11, is increased in intensity so that more electrons pass through the control electrode and through anode apertures 34 and 35 and enter the second beam interaction space 60 between retarding electrode 30 and focusing electrodes 29. This increases the space charge density within a limited portion 60a of interaction space 60 and causes the point of minimum potential within that space to migrate toward cathode 24; for example, the plane of minimum potential might move

from the location indicated in Figure 1 by dash line 61 to the location indicated by dash line 62. As a result, fewer electrons are able to leave interaction space portion 60a and traverse slots 34 and 35 to reach the first interaction space 63 between focusing electrode 17 and retarding electrode 18; in other words, the intensity of the second electron beam is reduced. However, as shown in Figure 2, the portion of the second electron beam which has been reduced in intensity does not extend into the portion 63a of interaction space 63 from which the electrons controlled in intensity by grid 32 emerge. Rather, the reduced-intensity portion of the second electron beam enters a different portion 63b of interaction space 63. Because fewer electrons from the second beam now enter beam-interaction space 63b, the potential minimum within that part of the first beam-interaction space tends to migrate toward retarding electrode 18 and the intensity of that portion of the first beam which passes through space 63b is increased. This intensified portion of the electron beam extends into a second portion 60b of interaction space 60 and acts to decrease the intensity of that part of the second electron stream which extends through interaction region 60b. So long as the product of the interaction factors of the two interaction regions 60 and 63 is greater than unity, the device functions as a cascade amplifier, the signal increasing in intensity until it finally appears in greatly amplified form as collected by anode 33.

It will be recognized that the signal appearing across load resistor 86, which is proportional to the beam current collected by anode 33, is of opposite polarity with respect to the signal applied to grid 32 from source 38. However, signals of the same polarity as the applied signal may be derived from the device if anode 33 is positioned to intercept the final portion of the beam generated by system 11 rather than the second beam, generated in system 12. To achieve this effect, anode 33 may be replaced by a similar anode 69 disposed intermediate retarding electrode 18 and anode 23 at the ends of those electrodes opposite control grid 32. For push-pull operation, a second control grid 68 may be mounted opposite grid 32 between anode 31 and focus electrodes 29, as indicated in Figure 2, and both anodes 33 and 69 may be provided so that fractional portions of both beams may be initially modulated and the amplified signal developed by both beams may be collected.

Separate bias source connections for retarding electrodes 18 and 30 are indicated in Figure 1, since minor variations in the potentials of those electrodes may be necessary to achieve optimum performance. Preferably, however, these electrodes should be operated at close to cathode potential and, for a given tube design, may well be grounded. It will be understood that although indirectly heated cathodes have been illustrated, directly heated emitters may be employed.

The embodiment of the invention illustrated in Figures 1 and 2 may be constructed to have a relatively high transconductance. More importantly, the relatively small sizes of the control electrodes and final anodes of the device result in substantially reduced grid-cathode and plate-cathode capacitances as compared to conventional tubes, so that the figure of merit of tube 10 is very high. Consequently, the tube functions efficiently as a broadband amplifier and may replace several stages of conventional amplifier circuits for a given application. The frequency range of the device is limited primarily by the effective beam-interaction time, that is to say, the upper frequency limit for effective operation of the device depends upon the time necessary for changes in space charge density in the interaction or virtual cathode regions 60 and 63 to be reflected in changes in beam intensity. For electrode dimensions similar to those of the commercially available 6BN6, effective operation may be achieved at least as high as the intermediate frequency of 41.25 megacycles normally employed in domestic tele-

vision receivers. Practical manufacturing considerations are the principal controlling factors with respect to frequency range; generally speaking, the smaller the electrode slot dimensions and the smaller the spacing between electrodes, the higher the effective frequency range.

The increase in gain achieved in tube 10, as compared to tube 39 of Figure 3, results from the fact that individual portions or increments of each of the electron beams intercept more than one similar increment of the other beam. Thus, in Figure 2 the vertical increment of the beam from gun 11 indicated by dash lines 65 intercepts increments of the beam from gun 12 as shown by dash lines 66 and 67. The angular inclination of the paths of the two beams within their common center plane A, which results from the angular displacement of gun 11 and electrode system 21 with respect to gun 12 and system 36 by angle θ , comprises one simple and effective means for cascading the two beams. The same effect may, of course, be obtained by substituting a multiplicity of electron guns and electrode systems for the illustrated components 11, 12, and 21, 36 so that individual electron beams are substituted for the increments of the two beams developed in tube 10. Moreover, it is not essential that the beams of a device such as tube 10 follow a common center plane, so long as increments of each beam intercept respectively different increments of the other beam in the two different interaction regions.

Still another means for achieving cascaded gain is schematically illustrated in the embodiment of Figure 5, which is in many respects similar to that of Figure 1. The individual elements of electron guns 11 and 12 and electrode systems 21 and 36 are included in the electron tube 70 illustrated in Figure 5; as before, the individual electrodes are symmetrically arranged about center plane A. For convenience, the additional control electrode 68 and anode 69 necessary for push-pull operation have been omitted from Figure 5. Other minor modifications have been illustrated; for example, the leads for focus electrodes 15, 17, 25 and 29 are brought out separately and are connected to potential sources which are negative with respect to cathode potential. More importantly, and as more clearly indicated in the view of Figure 6, in tube 70 the electron guns and associated electrode systems are not angularly displaced with respect to one another. Instead, the offset relationship of individual increments of the electron beams necessary for effective cascade amplification is achieved by individually deflecting the two electron streams.

A first magnetic deflection system, schematically illustrated by a pair of pole pieces 71 and 72, is mounted adjacent electrode system 21. A similar magnetic deflection system comprising pole pieces 73 and 74 is associated with electrode system 36. The two magnetic deflection systems may be relatively simple in form and may comprise permanent magnet structures essentially similar to the ion-trap devices familiar in the cathode-ray tube art. The first magnetic deflection system 71, 72 develops a first magnetic field, generally indicated by arrow 75, which tends to deflect the electron beam from gun 11 upwardly as indicated by dash lines 76 in Figure 6. The magnetic field developed by system 73, 74 is of opposite sense, as indicated by arrow 77 in Figure 5, so that the individual increments of the beam from gun 11 are deflected in the opposite direction as they enter the region between anode 31 and retarding electrode 30, as indicated by the extensions of dash lines 76 in Figure 6.

The effect of the magnetic fields in tube 70 upon the electron beam from gun 12 is illustrated in Figure 6 by dash-dot lines 78. Because this electron stream traverses the magnetic fields in the opposite direction from the first beam, it is deflected in the opposite sense by each magnetic field. Consequently, as the electron beam from gun 12 enters the field of magnetic deflection 73, 74 it is deflected upwardly; subsequently, as this beam enters the field of system 71, 72, the sense of the deflection is

reversed. Accordingly, it will be seen that the magnetic deflection systems segregate the two beams in accordance with their direction of movement so that individual increments of each of the electron beams developed in tube 70 intercept more than one corresponding increment of the other of the electron beams so that cascade action is achieved. In other words, each increment of the electron beam from gun 11 may be said to coincide with one increment of the beam from gun 12 in interaction region 63; the same increment of the beam from gun 11 is coincident with an entirely different increment of the beam from gun 12 in interaction region 60.

In all other material respects, the operation of tube 70 may be essentially similar to that of tube 10, so that the functional description of the tube need not be repeated. Tube 70 may be somewhat simpler to construct, since it is not necessary to angularly displace the electron guns and their associated electrode systems with respect to each other. Moreover, if electromagnetic deflection systems are substituted for the permanent magnet structure 71-74, the offset of the individual increments of the two electron beams with respect to each other may be adjusted for optimum performance.

While particular embodiments of the present invention have been shown and described, it is apparent that changes and modifications may be made without departing from the invention in its broader aspects. The aim of the appended claims, therefore, is to cover all such changes and modifications as fall within the true spirit and scope of the invention.

I claim:

1. An electron-discharge device comprising: means including a first electron gun for projecting a first sheet-like beam of electrons along a first reference path; means including a second electron gun for projecting a second sheet-like beam of electrons along a second reference path, a part of which is coincident with a part of said first reference path; means, including an additional electrode system encompassing coincident parts of said reference paths and comprising a retarding electrode associated with and co-operating with said second electron gun, for establishing a virtual cathode region in which the intensity of said second electron beam is determined by the intensity of said first electron beam through direct electron-interaction between said beams; control means coupled to at least a portion of said first beam and responsive to an applied signal for controlling the intensity of said portion of said first electron beam; and output means coupled to at least a portion of one of said beams for deriving an output signal therefrom.

2. An electron-discharge device comprising: means including a first electron gun for projecting a first sheet-like beam of electrons along a first reference path; means including a second electron gun for projecting a second sheet-like beam of electrons along a second reference path, a part of which is coincident with a part of said first reference path; means including an additional electrode system encompassing coincident parts of said reference paths and comprising a retarding electrode associated with and co-operating with said second electron gun for establishing a virtual cathode region in which the intensity of said second electron beam is determined by the intensity of said first electron beam through direct electron-interaction between said beams; a control electrode disposed transversely of at least a portion of said first reference path and responsive to an applied signal to control the intensity of said portion of said first electron beam; and output means coupled to at least a portion of one of said beams for deriving an output signal therefrom.

3. An electron-discharge device comprising: means including a first electron gun for projecting a first sheet-like beam of electrons along a first reference path; means including a second electron gun for projecting a second sheet-like beam of electrons along a second reference path,

a part of which is coincident with a part of said first reference path; means, including an additional electrode system encompassing coincident parts of said reference paths and comprising a retarding electrode associated with and co-operating with said second electron gun, for establishing a virtual cathode region in which the intensity of said second electron beam is determined by the intensity of said first electron beam through direct electron-interaction between said beams; control means coupled to at least a portion of said first beam and responsive to an applied signal for controlling the intensity of said portion of said first electron beam; and a collector electrode, disposed transversely of at least a portion of one of said reference paths, for intercepting at least a portion of one of said beams to derive an output signal therefrom.

4. An electron-discharge device comprising: means including a first electron gun for projecting a first sheet-like beam of electrons along a first reference path; means including a second electron gun for projecting a second sheet-like beam of electrons along a second reference path, a part of which is coincident with a part of said first reference path; means, including an additional electrode system encompassing coincident parts of said reference paths and comprising an accelerating electrode, focusing means, and a retarding electrode associated with and co-operating with said second electron gun, for establishing a virtual cathode region in which the intensity of said second electron beam is determined by the intensity of said first electron beam through direct electron-interaction between said beams; control means coupled to at least a portion of said first beam and responsive to an applied signal for controlling the intensity of said portion of said first electron beam; and output means coupled to at least a portion of one of said beams for deriving an output signal therefrom.

5. An electron-discharge device comprising: means including a first electron gun for projecting a first sheet-like beam of electrons along a first reference path; means including a second electron gun for projecting a second sheet-like beam of electrons along a second reference path, a part of which is coincident with a part of said first reference path; means for segregating said two electron beams; means, including an additional electrode system encompassing coincident parts of said reference paths and comprising a retarding electrode associated with and co-operating with said second electron gun, for establishing a virtual cathode region in which the intensity of said second electron beam is determined by the intensity of said first electron beam through direct electron-interaction between said beams; control means coupled to at least a portion of said first beam and responsive to an applied signal for controlling the intensity of said portion of said first electron beam; and output means coupled to at least a portion of one of said beams for deriving an output signal therefrom.

6. An electron-discharge device comprising: means including a first electron gun for projecting a first sheet-like beam of electrons along a first reference path; means including a second electron gun for projecting a second sheet-like beam of electrons along a second reference path, a part of which is coincident with a part of said first reference path; means, including a magnetic deflection system, for segregating the electrons of said two beams in accordance with their direction of movement; means, including an additional electrode system encompassing coincident parts of said reference paths and comprising a retarding electrode associated with and co-operating with said second electron gun, for establishing a virtual cathode region in which the intensity of said second electron beam is determined by the intensity of said first electron beam through direct electron-interaction between said beams; control means coupled to at least a portion of said first beam and responsive to an applied signal for controlling the intensity of said portion of said first electron beam; and output means coupled to at least a portion of one of said beams for deriving an output signal therefrom.

a portion of one of said beams for deriving an output signal therefrom.

7. An electron-discharge device comprising: means including a first electron gun for projecting a first sheet-like beam of electrons along a first reference path; means including a second electron gun for projecting a second sheet-like beam of electrons along a second reference path, angularly displaced with respect to said first path; means, including a magnetic deflection system coupled to said two electron beams, for segregating the electrons of said two beams in accordance with their direction of movement and for deflecting said first beam so that a part of its path of movement coincides with a part of said second reference path; means, including an additional electrode system encompassing coincident parts of said reference paths and comprising a retarding electrode associated with and co-operating with said second electron gun, for establishing a virtual cathode region in which the intensity of said second electron beam is determined by the intensity of said first electron beam through direct electron-interaction between said beams; control means coupled to at least a portion of said first beam and responsive to an applied signal for controlling the intensity of said portion of said first electron beam; and output means coupled to at least a portion of one of said beams for deriving an output signal therefrom.

8. An electron-discharge device comprising: means including a first electron gun for projecting a first sheet-like beam of electrons along a first reference path; means including a second electron gun for projecting a second sheet-like beam of electrons along a second reference path with increments of each of said electron beams intercepting more than one similar increment of the other of said beams; means, including two additional electrode systems associated with and co-operating with said electron guns, for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; and output means coupled to at least a portion of one of said beams for deriving an output signal therefrom.

9. An electron-discharge device comprising: means including a first electron gun for projecting a first sheet-like beam of electrons along a first reference path centered about a given reference plane; means including a second electron gun for projecting a second sheet-like beam of electrons in opposition to said first beam along a second reference path centered about said reference plane with increments of each of said electron beams intercepting more than one similar increment of the other of said beams; means, including two additional electrode systems associated with and co-operating with said electron guns for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; and output means coupled to at least a portion of one of said beams for deriving an output signal therefrom.

10. An electron-discharge device comprising: means including a first electron gun for projecting a first sheet-like beam of electrons along a first reference path; means including a second electron gun for projecting a second sheet-like beam of electrons along a second reference path with increments of each of said electron beams intercepting more than one similar increment of the other of said beams; means including two additional electrode systems associated with and co-operating with said electron guns, for establishing two spaced electron-interaction regions in each of which the electrons in one of said beams are directly controlled by the electrons in the other of said beams; means, including a control electrode

disposed transversely of a fractional portion of said reference path and coupled to only a fractional portion of said first beam, responsive to an applied signal for modulating said portion of said first electron beam; and output means coupled to at least a portion of one of said beams for deriving an output signal therefrom.

11. An electron-discharge device comprising: means including a first electron gun for projecting a first sheet-like beam of electrons along a first reference path; means including a second electron gun for projecting a second sheet-like beam of electrons along a second reference path with increments of each of said electron beams intercepting more than one similar increment of the other of said beams; means including two additional electrode systems associated with and co-operating with said electron guns, for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; means including a collector electrode disposed transversely of a fractional portion of one of said reference paths, for intercepting only a fractional portion of one of said beams to derive an output signal therefrom.

12. An electron-discharge device comprising: means including a first electron gun for projecting a first sheet-like beam of electrons along a first reference path; means including a second electron gun for projecting a second sheet-like beam of electrons along a second reference path with increments of each of said electron beams intercepting more than one similar increment of the other of said beams; means, including two additional electrode systems, each comprising a focusing electrode and a retarding electrode, associated with and co-operating with said electron guns for establishing two spaced virtual cathode regions in each of which the intensity of one of said beams is determined by the intensity of the other of said beams through direct electron-interaction between said beams; control means coupled to at least a portion of said first beam and responsive to an applied signal for modulating said portion of said first electron beam; and output means coupled to at least a portion of one of said beams for deriving an output signal therefrom.

13. An electron-discharge device comprising: means including a first electron gun for projecting a first sheet-like beam of electrons along a first reference path centered about a given reference plane; means including a second electron gun for projecting a second sheet-like beam of electrons in opposition to said first beam along a second reference path centered about said reference plane; means for deflecting said two beams within said plane so that increments of each of said electron beams intercept more than one similar increment of the other of said beams; means, including two additional electrode systems associated with and co-operating with said electron guns, for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; and output means coupled to at least a portion of one of said beams for deriving an output signal therefrom.

14. An electron-discharge device comprising: means including a first electron gun for projecting a first sheet-like beam of electrons along a first reference path centered about a given reference plane; means including a second electron gun for projecting a second sheet-like beam of electrons in opposition to said first beam along a second reference path centered about said reference plane; means, including a magnetic deflection system, for segregating the electrons of said two beams in accordance with their direction of movement and for deflecting said two beams so that increments of each of said beams in-

tercept more than one similar increment of the other of said beams; means, including two additional electrode systems associated with and co-operating with said electron guns for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; and output means coupled to at least a portion of one of said beams for deriving an output signal therefrom.

15. An electron-discharge device comprising: means including a first electron gun for projecting a first sheet-like beam of electrons along a first reference path centered about a given reference plane; means including a second electron gun for projecting a second sheet-like beam of electrons in opposition to said first beam along a second reference path centered about said reference plane, the electrodes of said second electron gun being angularly displaced with respect to the electrodes of said first electrode system so that said second reference path intersects said first reference path at an acute angle within said plane with increments of each of said electron beams intercepting more than one similar increment of the other of said beams; means, including two additional electrode systems associated with and co-operating with said electron guns for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; and output means coupled to at least a portion of one of said beams for deriving an output signal therefrom.

16. An electron-discharge device comprising: means including a first electron gun for projecting a first sheet-like beam of electrons along a first reference path; means including a second electron gun for projecting a second sheet-like beam of electrons along a second reference path with increments of each of said electron beams intercepting more than one similar increment of the other of said beams; means, including two additional electrode systems associated with and co-operating with said electron guns, for establishing two spaced electron-interaction regions in each of which the electrons in one of said

beams are directly controlled by the electrons in the other of said beams; means, including a control grid disposed transversely of a fractional portion of said reference path and coupled to only a fractional portion of said first beam, responsive to an applied signal for intensity-modulating said portion of said first electron beams; means, including a second control grid disposed transversely of a fractional portion of said second reference path and coupled to only a fractional portion of said second beam, responsive to an applied signal for intensity-modulating said portion of said second electron beam; and output means coupled to at least a portion of one of said beams for deriving an output signal therefrom.

17. An electron-discharge device comprising: means including a first electron gun for projecting a first sheet-like beam of electrons along a first reference path; means including a second electron gun for projecting a second sheet-like beam of electrons along a second reference path with increments of each of said electron beams intercepting more than one similar increment of the other of said beams; means, including two additional electrode systems associated with and co-operating with said electron guns, for establishing two spaced electron-interaction regions in each of which the electrons in one of said beams are directly controlled by the electrons in the other of said beams; control means coupled to at least a portion of said first beam and responsive to an applied signal for modulating said portion of said first electron beam; means, including a first collector electrode disposed transversely of a fractional portion of said first reference path, for intercepting only a fractional portion of said first beam to derive a first output therefrom; and means, including a second collector electrode disposed transversely of a fractional portion of said second reference path, for intercepting only a fractional portion of said second beam to derive a second output signal therefrom.
